DESIGN FOR A FINGER RING

Henry J. Jung, Milwaukee, Wis.

Application July 19, 1945, Serial No. 120,811

Term of patent 14 years

(Cl. D45—10)

To all whom it may concern:

Be it known that I, Henry J. Jung, a citizen of the United States, residing at Milwaukee, in the county of Milwaukee and State of Wisconsin, have invented a new, original, and ornamental Design for a Finger Ring, of which the following is a specification, reference being had to the accompanying drawing, forming part thereof.

In the drawing:

Fig. 1 is a perspective view of a finger ring showing my new design;

Fig. 2 is an enlarged edge view of the finger ring, with a portion thereof shown in broken lines for illustrative purposes, the portion shown in full lines being repeated around the ring's circumference; and

Fig. 3 is a sectional view taken on line 3—3 of Fig. 2.

I claim:

The ornamental design for a finger ring, substantially as shown and described.

HENRY J. JUNG.
